UNITED STATES PATENT OFFICE.

CLYDE R. WORK, OF YOUNGSTOWN, OHIO.

MAGAZINE WRENCH.

Application filed December 31, 1924. Serial No. 759,075.

The present invention provides a tool of the nature of a spanner or nut wrench which embodies provision for receiving a cap screw or a plurality of nuts and which is of special advantage when changing pneumatic tires or performing other work requiring the loosening and tightening of a number of nuts, screws and bolts.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is a side view of the preferred form of tool, the pressure piece being in section,

Figure 2 is an end view of the holder for the bolts and nuts, showing a portion of the brace,

Figure 3 is an enlarged longitudinal sectional view of the nut and bolt holder having a portion of the brace attached,

Figure 4 is an enlarged sectional view on the line 4—4 of Figure 1, and

Figure 5 is an enlarged sectional view on the line 5—5 of Figure 1.

Corresponding and like parts are referred to in the following description and designated in the several views of the drawings by like reference characters.

The numeral 10 designates the holder for the nuts, bolts, screws, and the like, the same being tubular and constituting a magazine, and for convenience of operation an ordinary brace 11 is attached at one end to an end of the holder 10, the latter being closed at one end by means of a plug 12 through which the holder passes an end of the brace 11 which is made secure by means of a rivet or pin 13. The outer or working end of the holder 10 is reinforced by means of a ferrule or band 14 which has a portion cut away as indicated at 15 to receive a spring 16 which normally exerts a pressure upon a retainer 17 to hold it projected into the ball or opening of the holder 10 to prevent

outward displacement of the nuts, bolts or screws placed within the holder or received therein when removed from the cooperating part, thereby obviating the necessity of receiving the same in the hand which is objectionable, particularly when changing tires or performing other work when it is desired not to soil the hands. The retainer 17 preferably consists of a ball.

A release 18 is disposed at one side of the holder 10 and is mounted in the ferrule or band 14 and is provided at one end with a crank and at the opposite end with a lift 19 which is disposed beneath the free end of the spring 16 so that when the crank of the release is moved outwardly, the free end of the spring 16 is correspondingly thrown outward thereby relieving the retainer 17 of inner pressure so that the nuts, screws, or the like contained within the holder may readily discharge. The crank portion of the release normally lies against the side of the holder thereby preventing accidental operation thereof or injury thereto by striking an object.

It will be understood that the release 18 is to be used only when it is desired to empty the magazine when it is not of sufficient capacity to hold all of the nuts in an unscrewing operation, as for instance in removing the head bolts of an internal combustion engine. In screwing on nuts from the magazine it will be apparent that the bolt end will engage with the first nut in the magazine and will be pulled down as the nut is screwed down on the bolt and the wrench will be self releasing.

A follower 20 is located within the holder 10 and is normally pressed outwardly by means of a coil spring 21 which is soldered or otherwise attached at its inner end to the plug 12 and at its outer end to the follower 20 and this spring normally urges the discharge of an article contained within the holder, casual displacement of such article being prevented by the retainer 17, but which yields to admit of entrance or removal of the article by the application of sufficient force thereto.

What is claimed is:—

A device of the class described comprising a magazine having an opening through the side thereof to its holding chamber, a retainer for the lowermost article in said chamber occupying said opening, a con-

tractile spring surrounding the chamber and being in contact with the retainer to hold it in place and permit yielding thereof, said magazine having a band surrounding the same, said band having a recess accommodating said spring, and a release member carried by said band, said member

having a spring displacing element located intermediate a portion of the spring and the exterior of the magazine.

10

In testimony whereof I affix my signature.

CLYDE R. WORK.
